TOY RECORD PLAYER

William Eugene Critzer, New York, N. Y.

Application September 23, 1954, Serial No. 32,405

Term of patent 14 years

(Cl. D56—1)

The essential features of my design reside in those portions shown in full lines.

I claim:

The ornamental design for a toy record player, as shown and described.
